CLAIM

The ornamental design for a portable computer housing, as shown and described.

DESCRIPTION

FIG. 1 is a right front and top perspective view of the portable computer housing with the cover in the opened position;

FIG. 2 is a rear left side and bottom perspective view thereof;

FIG. 3 is a front elevational view thereof;

FIG. 4 is a top plan view thereof;

FIG. 5 is a right side elevational view thereof;

FIG. 6 is a left side elevational view thereof;

FIG. 7 is a rear elevational view thereof;

FIG. 8 is a bottom plan view thereof;

FIG. 9 is a right front and top perspective view thereof with the cover in the closed position;

FIG. 10 is a rear left side and bottom perspective view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top plan view thereof; and,

FIG. 16 is a bottom plan view thereof.

FIGS. 1 and 2 are drawn on a reduced scale.
